DRAWPLATE MADE OF REMOVABLE ELEMENTS FOR THE MASS PRODUCTION OF VARIOUS CERAMIC WARE

René Martin, Asnières, France

Application August 4, 1950, Serial No. 177,734
In France August 17, 1949

5 Claims. (Cl. 25—17)

1

My invention has for its object a drawplate for the mass production of ceramic ware of all types, shapes and outlines such as facing bricks, facing blocks, bricks whether solid, perforated or hollow, hollow brickworks of all types, laths, drawn tiles and more particularly facing bricks of the tenon and mortise type as disclosed in my co-pending application, Serial No. 154,083, filed on April 5, 1950, now abandoned.

It is a known fact that in the prior technique of production of ceramic ware through drawing as still used nowadays, one is constrained to produce a complete and special drawplate for each outline which leads to the necessity of producing and keeping up a considerable amount of implementing that is costly and cumbersome, while complete changes in drawplates have to be proceeded with each time it is necessary to produce a different outline and consequently lengthy stoppages arise in manufacture and considerable losses of time are to be taken into account.

My invention has for its object a drawplate for the mass production of ceramic ware, said drawplate being constituted by a support carried by the actual die at the output end of the latter while removable elements are fitted over said support and provide after their assembly the shape or outline that it is desired to give to the ceramic ware passing out of the drawplate.

This novel technique allows producing ceramic ware assuming any possible outline while resorting to a single dieplate as it is sufficient to replace on the support one removable element by another in order to produce the desired modification in outline within the shortest time possible while using an extremely simple, light arrangement the bulk of which is extremely small.

It is thus possible to give the support various geometrical shapes whether square, parallel-opedic, round, half round, triangular, trapezium shaped or the like. It is also possible to modify the shape and cross-section of the removable element and also to assemble and secure said elements to the support either through notch-shaped slideways or through pins, screws or bolts or again through clamping hooks, lugs, keys or the like securing or hooking means.

In a preferred embodiment of my invention, the support is provided laterally with notch-shaped slideways that mate exactly the shape of the interchangeable elements adapted to be fitted therein, each notch showing a bearing on which is positioned the removable element that is held and clamped thereon by projections forming slideways and stops.

2

In order to provide for a rigid assembly of the removable elements fitted inside the support, I may use one or more pins or the like equivalent mechanical means allowing a rapid change of either interchangeable element.

I will describe hereinafter with reference to accompanying drawings an embodiment of the invention as applied to a drawplate intended for the production of blocks of facing bricks the sides of which are 22 cm. long and that are provided with tenons and mortises for engagement with one another.

In said drawings:

Fig. 1 is an elevational view of the support.

Fig. 2 is a side view thereof.

Fig. 3 is a perspective view of a part thereof.

Figs. 4 and 5 are cross-sections through lines IV—IV and V—V (Fig. 1) of the support with sloping slideways thereon.

Fig. 6 is an elevational front view of the removable elements fitted over the support.

Fig. 7 is a plan view of the tenoned member, the dotted line showing a bevelled part directed towards the inside of the drawplate.

Fig. 8 is a cross section of the support with a removable element defining the facing, that is fitted and secured through a pin.

Fig. 9 shows separately in plan view, the said member.

Lastly, Fig. 10 is a perspective view of the draw plate mounted on the die adapted to be secured to the opening of the molding machine.

The support may be inserted in or made in one with the die member of the draw plate that is to be fitted on the molding machine and it is constituted in the example illustrated by a square shaped part 1 that may however assume as stated any other geometrical shape and it is provided essentially at its corners with four triangular prisms 2, 3, 4 and 5.

The sides of each prism are arranged in a manner such that one of the latter is perpendicular to one side of the internal outline of the support at the corner considered while the adjacent face is sloping so as to form an angle adapted to make the fitting of the removable elements easier; thus for each side of the square shaped member 1, there is at one end a face 6 of one prism that is perpendicular to the side of the square defined by the support and at the opposite end a sloping face 7 on the prism facing the first prism. The four prisms 2, 3, 4, 5 are interconnected transversely through the shoes 8 the outer surfaces of which are sloping so as to further the easy fitting of the removable elements

and through further inner shoes 8' that are flat and form the bottom surface of the fitting and serve as a base at 9 for the removable elements.

These shoes are provided at each end with slideways 10 and 11 the projections 12 on which form stops, said slideways being adapted to receive the interchangeable elements 13, 14, 15 and 16 matching exactly their shape, each of said elements as illustrated in Figs. 7 and 8 is provided at one end with a flange 17 adapted to engage one of the slideways 10 and at the other end, with a flange 18 sloping with a predetermined obliquity, in the present case 120°, and engaging the other slideway 11.

In Fig. 6 the elements 13, 14, 15, and 16 are shown as positioned on the support 1 and secured rigidly thereto by means of pins 19 passing through perforations 20 in the support and through the perforations 21 of the removable elements. They define thus the output of the draw-plate for the production of a facing block of the type disclosed in my above mentioned co-pending application. For this purpose the interchangeable element 13 (Fig. 9) is provided with a plurality of recesses 22 adapted to mold the thicknesses of the different bricks appearing in the block and with a corresponding series of projections 23 adapted to mold the dummy joints and also with the half projections lying at each end of the element 13 and adapted to produce the two dummy half joints at the ends of the facing block.

The interchangeable element 14 includes a recess 24 adapted to form in the complete brick a double tenon jaw, said recess registering with the recessed portion 25 in the support 1.

The element 15 is provided on its inner surface with a shouldered projection 26 adapted to form the mortise in the facing block of the mortise and tenon type.

What I claim is:

1. A drawplate for the production of ceramic ware in combination with a die comprising an open support fitted at the output of the die and including at its apices sideways interconnected by shoes so as to form slideways and removable elements engaging said slideways to define therewith the shape and outline required for giving the desired form to the ceramic ware passing out of the die and stops rigid with the slideways in register with the slideways for holding the removable elements in the latter.

2. A drawplate for the production of ceramic ware in combination with a die comprising an open support fitted at the output of the die and including at its apices prisms interconnected by shoes so as to form slideways and removable elements engaging said slideways to define therewith the shape and outline required for giving the desired form to the ceramic ware passing out of the die and stops rigid with the slideways in register with the slideways for holding the removable elements in the latter.

3. A drawplate for the production of ceramic ware in combination with a die comprising an open support fitted at the output of the die and including at its apices sideways interconnected by shoes so as to form slideways and removable

elements engaging said slideways to define therewith the shape and outline required for giving the desired form to the ceramic ware passing out of the die and stops rigid with the slideways in register with the slideways for holding the removable elements in the latter, and at least one pin securing each removable element to the corresponding part of the support.

4. In a drawplate for ceramic ware, the combination of a die, a polygonal open support fitted at the outlet of the die and including at its apices substantially triangular prisms of which one side is perpendicular to the adjacent side of the polygonal support while the other side is oblique with reference to the adjacent side of the polygonal support, and at least one transverse member interconnecting two successive prisms along the corresponding side of the polygonal support and provided with a bearing surface parallel with the side considered and adapted to be engaged by an interchangeable element, and an interchangeable element adapted to be fitted over each transverse member while engaging the bearing thereon and being held between the corresponding sides of the prisms at either end of said transverse member, the associated interchangeable elements defining the shape given to the cross-section of the ceramic ware fed by the die.

5. In a drawplate for ceramic ware, the combination of a die, a polygonal open support fitted at the outlet of the die and including at its apices substantially triangular prisms of which one side is perpendicular to the adjacent side of the polygonal support while the other side is oblique with reference to the adjacent side of the polygonal support, the perpendicular and oblique sides of the prism following one another in the same direction throughout the periphery of the support and at least one transverse member interconnecting two successive prisms along the corresponding side of the polygonal support and provided with a bearing surface parallel with the side considered and adapted to be engaged by an interchangeable element, and an interchangeable element adapted to be fitted over such transverse member, while engaging the bearing thereon and being held between the corresponding sides of the prisms at either end of said transverse member, the associated interchangeable elements defining the shape given to the cross section of the ceramic ware fed by the die.
